UNITED STATES PATENT OFFICE.

MAX COHEN, OF DENVER, COLORADO.

EYESHADE.

Application filed January 8, 1925. Serial No. 1,197.

To all whom it may concern:

Be it known that I, MAX COHEN, citizen of the United States, residing at Denver, the city and county of Denver and State of Colorado, have invented certain new and useful Improvements in Eyeshades; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to improvements in eye shades of the type employed by tennis and polo players, automobile drivers, etc.

There are many occasions where it is 20 desirable and necessary to protect the eyes against the effect of strong sunlight and at the same time leave the head practically uncovered so as to permit the cooling effect of the breezes to be effective. Tennis and polo players in most cases prefer to have 25 their heads uncovered but at the same time they find it necessary to provide shade for the eyes. The ordinary eye shades, such as are sold for use in offices, are not satisfactory for outside use where the wearer 30 participates in some strenuous game, for several reasons, among which may be mentioned that these shades have a tendency to work downwardly until they interfere with the vision of the wearer. Another reason 35 why the ordinary eye shade is unsuited for outside use is that it permits flies, mosquitoes and other insects to light on the wearer's head or hair where they cause considerable annoyance until they have been 40 chased away.

It is the object of this invention to produce an eye shade that shall afford the desired protection against the action of the sun and shall be so constructed that it will 45 not slide down over the wearer's eyes or prevent the access of air to the wearer's head while at the same time it will protect the wearer against annoyance from flies or insects.

50 In order better and more clearly to describe my invention and the preferred man-

ner of constructing and using the same, I shall have reference to the accompanying drawing in which the preferred embodiment thereof is shown and in which—⁵⁵

Fig. 1 is a perspective view of my improved eye shade and

Fig. 2 shows the shade in place on the wearer's head.

My improved shade may be made of any 60 suitable material but is preferably constructed of cloth, such as, white flannel and comprises a visor 5 constructed like the visor of an ordinary cap and consists of a central member 6 of stiff material which is 65 enclosed between the two layers of cloth. Secured to the upper edge of the visor is a band of flannel or other fabric. To the ends of this band elastic bands 8 and 9 are attached and the ends of which are adjustably 70 connected by means of a metal slide 10. Secured to the upper edge of the band 7 is a piece of netting 11 which is adapted to fit against the head when the shade is worn, in the manner shown in Fig. 2. The netting 75 11 prevents the shade from being pulled down too far and also prevents flies and other insects from biting the head and causing annoyance while at the same time it permits free circulation of air. It will be so noted that the net 11 extends only part way back as this is all that is necessary in order to accomplish the function that is intended. The fact that the netting covers only a portion of the top of the head also 85 permits the shade to be readily adjusted to fit various sizes of heads.

Having now described my invention what I claim as new is:

An eye shade comprising a visor, a band 90 connected therewith and adapted to extend around the back of the head, said band being extensible to fit heads of varying size, and a covering for the head connected with the visor, extending rearwardly therefrom over 95 the top of the head and terminating in an edge a short distance above the extensible band, the ends of said edge being at the opposite sides of the head.

In testimony whereof I affix my signature.¹⁰⁰

MAX COHEN.
